UNITED STATES PATENT OFFICE.

ROY FISHER, OF LOS ANGELES, CALIFORNIA.

DESIGN FOR A COMBINED RADIATOR-CAP ORNAMENT AND TRAFFIC SIGNAL.

Application filed February 10, 1928. Serial No. 25,355. Term of patent 7 years.

To all whom it may concern:

Be it known that I, ROY FISHER, a citizen of the United States, residing at Los Angeles, in the county of Los Angeles, and State of California, have invented a new, original, and ornamental Design for a Combined Radiator-Cap Ornament and Traffic Signal, of which the following is a specification, reference being had to the accompanying drawing, forming part thereof.

Fig. 1, is a perspective view of a combined radiator cap ornament and traffic signal, showing my new design.

Fig. 2, is a rear view of the same.

I claim:

The ornamental design for a combined radiator cap ornament and traffic signal, substantially as shown.

ROY FISHER.
